UNITED STATES PATENT OFFICE

JOSEPH E. STRAUB, OF SYRACUSE, NEW YORK, ASSIGNOR TO REMINGTON TYPE-WRITER COMPANY, OF ILLION, NEW YORK, A CORPORATION OF NEW YORK

TYPEWRITING MACHINE

Application filed June 7, 1927. Serial No. 197,063.

My invention relates to typewriting and like machines and pertains more particularly to means for mounting and guiding levers or pivoted members in such machines. 5 In some typewriting machines the construction is such that keys in the keyboard, other than those actuated, will "wink", quiver, vibrate or move during the actuation of the machine, diverting the operator's attention from 10 the work in hand and causing considerable annoyance.

Attempts have been made to overcome this disadvantage by holding the thickness of the key lever stock to closer limits and providing 15 closer bearings and guides for said levers. But this has proved vexatious, insufficient and impracticable.

The main object of my invention is to provide a simple, inexpensive, yet highly efficient 20 means for overcoming the disadvantages pointed out above.

To the above and other ends which will hereinafter appear, my invention consists in the features of construction, arrangements of 25 parts, and combinations of devices, set forth in the following specification and particularly pointed out in the appended claims.

In the accompanying drawings, wherein like reference characters designate corresponding parts in the different views:

Figure 1 is a bottom plan view of a system of key levers of a typewriting machine mounted and guided in accordance with my invention.

Figure 2 is an enlarged, detail, fragmentary, sectional view of a portion of the construction shown in Fig. 1, the section being taken on the line 2-2 of Fig. 3, and looking in the direction of the arrows at said line.

Figure 3 is an enlarged, detail, fragmentary, fore-and-aft, vertical sectional view of the same taken on the line 3-3 of Fig. 1 and looking in the direction of the arrows at said line.

Figure 4 is an enlarged, detail, fragmentary, perspective view of the combined pivot bearing and comb, together with some of the associated parts.

I have shown my invention embodied, in 50 the present instance, in a Remington portable

typewriting machine, only so much of said machine being shown as is necessary to illustrate the invention in its embodiment therein. It should be understood, however, that the invention is not restricted to inclusion in such 55 machine, but may be used in typewriting or like machines generally, wherever found available.

As shown in the present instance, the members to be guided and controlled are substantially horizontally disposed key levers 1 that extend fore-and-aft of the machine. Those levers 1 at the sides of the system extend from near the front end portions thereof, indicated at 2, in converging planes to the rear pivoted ends thereof. On the other hand, the key levers 1 at and near the center of the system are arranged in vertical fore-and-aft parallel planes. Each key lever is provided at its front end with a finger key 3 and is apertured at its rear end, as indicated at 4, to provide a bearing opening to receive a pivot rod 5.

The pivot rod is supported by a combined pivot rod support and guide comb, designated as a whole by the reference numeral 6 and preferably made of sheet metal. This member 6 is provided with foot pieces 7 pierced to receive headed screws 8 by which said member may be firmly secured to the usual casting 75 9 fixed to the frame of the machine and of which supporting segments 10 and 11 form part. The member 6 is provided near the ends thereof with two oppositely curved adjacent supporting figures 12 and 13 that receive and support the pivot rod 5 near the ends thereof. Extending across the axis of the pivot rod 5, beyond its ends, are two retaining fingers 14 at the ends of the member 6. These retaining fingers, when in position 80 for use and with the pivot rod 5 in place, prevent an axial displacement of said rod. When one of the fingers 14 is bent to one side, a longitudinal displacement and removal of the pivot rod may be effected.

The pivot rod 5 is also supported substantially throughout its length by guide arms, separating fingers or bearing members 15 and 16 depending from the member 6 and curved alternately in opposite directions to 100

provide seats for the pivot rod. While I have shown, in Fig. 1, a full complement of forty-two key levers it will be seen that there are but twenty-two separating fingers 15 and 16 employed in the present instance, every second separating finger or bearing member being removed or omitted to provide an intervening space at such point, as indicated at 17. Taking the place of the omitted guide or separating fingers at each of the points 17 is a spring means which coacts with adjacent levers 1 to bear laterally against them and hold them with a light pressure against the associated separating fingers or bearing members 15 and 16 which coact with said levers to receive the lateral thrust thereof away from each other. In the present instance, such spring means comprise a series of coiled expansion springs 18 which surround the pivot rod 5, and each of which is received in a space 17 where a finger has been omitted from the guide comb. Each of such springs 18 bears at one end laterally against an adjacent key lever 1 to force it with a light pressure to bear against a side edge or bearing wall 16^a of a separating finger 16, whereas, the opposite end of such spring bears laterally against the other adjacent key lever to force it with a light pressure against the side edge or bearing wall 15^a of the associated separating finger 15. It will be seen therefore that one spring 18 acts on two key levers to maintain them spaced apart and in lateral contact with their fixed bearing members, there being half the number of springs that there are key levers.

The front end portion of each key lever is received and works in a guide slot in the usual front guide comb 19, as shown in Fig. 1.

It will be understood that the springs 18 bearing lightly against the key levers axially of and near the pivot of said levers produces a slight lateral thrust against them which is resisted by the bearing members 15 and 16, thus taking up any lateral play or lost motion of the key levers without appreciably opposing the operating movement thereof, or rendering the type actions sluggish in operation.

It will be understood, moreover, that by this construction the key levers may be disposed at different angles to the axis of the pivot rod without the necessity of cutting guide slots in the comb at corresponding angles or having them unduly loose at their pivoted ends. Yet each lever will be effectively held and guided without undue restraint and a quivering of the keys in the keyboard will be efficiently prevented.

The construction is inexpensive to manufacture, easy to assemble, and has proven highly efficient in use.

Various changes may be made in the construction, and parts thereof may be employed

without others, without departing from my invention as it is defined in the accompanying claims.

What I do claim as new and desire to secure by Letters Patent, is:—

1. In a typewriting or like machine, the combination of a guide comb comprising a separating finger for the levers of each adjacent pair which coact therewith; levers coacting with and guided by said guide comb; and spring means exerting a spring pressure in opposite directions and laterally against the levers of each such pair to hold them with a light spring pressure against the opposite side walls of the intervening separating finger of the guide comb. 70

2. In a typewriting or like machine, the combination of a guide comb which has alternate separating fingers removed or omitted therefrom, a full complement of actuating levers coacting with said comb, and springs in said intervening spaces where the separating fingers are omitted and which exert their force laterally against said levers to hold them against the separating fingers of the 85 90 95 99 100 comb.

3. In a typewriting or like machine, the combination of a combined pivot support and guide comb having alternate separating fingers removed or omitted therefrom, a pivot rod around which the remaining separating fingers of the comb are bent alternately in opposite directions to support said pivot on the comb, a full complement of actuating levers mounted on said pivot rod, and spring means in said intervening spaces where the separating fingers are omitted and which exerts force laterally against the levers to hold them against the separating fingers of the comb. 100 105

4. In a typewriting or like machine, the combination of a combined pivot support and guide comb having alternate separating fingers removed or omitted therefrom, a pivot rod around which the remaining separating fingers of the comb are bent alternately in opposite directions to support said pivot on the comb, a full complement of actuating levers mounted on said pivot rod, and a series of coiled expansion springs surrounding said pivot rod, each spring being located in an intervening space where a separating finger is omitted and bearing laterally against two adjacent levers to hold them against the associated separating fingers. 110 115 120

5. In a typewriting or like machine, the combination of a combined pivot support and key lever guide comb made of sheet metal and having alternate separating fingers removed or omitted therefrom, a pivot rod around which the remaining separating fingers of the comb are bent alternately in opposite directions to support said pivot rod on the comb, a full complement of key levers mounted on said pivot rod and extending 125 130

- thereto in various planes, and a series of coiled expansion springs surrounding said pivot rod, each spring being located in an intervening space where a finger of the comb has been omitted and which exerts its force in opposite directions laterally against two adjacent key levers and tends to hold them against the sides of the associated fingers of the comb. 70
6. In a typewriting or like machine, the combination of a type bar, a manually operated actuating lever for the type bar, a fixed pivot on which said lever is adapted to turn, and a spring that exerts its force directly against said lever in the direction of and near the axis of said pivot. 75
7. In a typewriting or like machine, the combination of a type bar, a manually operated actuating lever for the type bar, a fixed pivot on which said lever is adapted to turn, a fixed bearing member that receives the lateral thrust of said lever in one direction, and a spring that bears laterally against the lever and holds it against said bearing member. 80
8. In a typewriting or like machine, the combination of a type bar, a manually operated actuating lever for the type bar, a fixed pivot on which said lever is adapted to turn, a fixed bearing member that receives the lateral thrust of said lever in one direction, and a coiled expansion spring that surrounds said pivot and bears laterally against the lever and holds it with a light pressure against said bearing member. 85
9. In a typewriting or like machine, the combination of a pair of type bars, a pair of adjacent manually operated actuating levers therefor, a fixed pivot on which said levers turn, a pair of fixed bearing members resisting the lateral thrust of said levers away from each other, and a spring intermediate said levers and exerting its force laterally thereof to hold the levers against said fixed bearing members. 90
10. In a typewriting or like machine, the combination of a pair of type bars, a pair of adjacent manually operated actuating levers therefor, a fixed pivot on which said levers turn, a pair of fixed bearing members resisting the lateral thrust of said levers away from each other, and a coiled expansion spring intermediate said levers and surrounding said pivot, the force of said spring being exerted against said levers to hold them against said fixed bearing members. 95
11. In a typewriting or like machine, the combination of a fixed pivot, a plurality of actuating levers mounted to turn on said pivot and disposed at different angles to the axis thereof, a plurality of fixed bearing members which receive the lateral thrust of said levers, and springs which exert their force laterally of said levers and tend to hold them against said fixed bearing members. 100
12. In the type actions of a typewriting or 105
13. In the type actions of a typewriting or like machine, the combination of a plurality of manually operated actuating levers, a fixed pivot therefor, a combined pivot support and guide comb, and spring means that exerts the force thereof laterally on each of said levers to hold it against one side wall of the associated separating member of the guide comb. 110
14. In the type actions of a typewriting or like machine, the combination of manually operated actuating levers, and intervening spring means acting against said levers in the direction of the pivotal axes of said levers for spacing said levers apart. 115
15. In a key actuated typewriting or like machine, the combination of printing instrumentalities, key actuated levers for operating said printing instrumentalities, and means for preventing a "winking" of said keys in the keyboard of the machine, such means comprising spring means that bear lightly and laterally against said levers in the general direction of the pivotal axes thereof. 120
- Signed at Syracuse, in the county of Onondaga and State of New York, this 2 day of June, A. D. 1927.
